UNITED STATES PATENT OFFICE

2,504,726

ROTARY DISH-WASHING MACHINE

Carl A. Philippi, New York, N. Y.

Application July 15, 1944, Serial No. 545,037

1 Claim. (Cl. 134—120)

1

This invention relates to dishwashers and refers more specifically to a container adapted to produce a cascading effect of water on the articles to be washed.

An object of the present invention is to provide an efficient dishwasher of simple design which shall be easy to manufacture and to use.

Another object is to provide a dishwasher extremely economical of soap and water.

Another object is to provide a dishwasher adapted to be operated by hand or by motor power.

Another object is to provide an efficient dishwasher which is easily portable and adapted for use with existing plumbing instead of requiring its own supply and drain pipes.

Other objects will become apparent from the following specification:

In accomplishing the objects of the present invention it was found desirable to provide a frame and a hollow body adapted to revolve in the frame, a body cover, a discharge spout, and means for holding the contents of the body in place. The body revolves about a horizontal axis.

In operation, the articles to be washed are placed in the body with several inches of hot soapy water. The cover is fixed in place and a few revolutions of the body washes the contents. The discharge cap is removed and the water run out by inverting the body.

The invention will appear more clearly from the following detailed description when taken in connection with the accompanying drawings showing, by way of example, preferred embodiments of the inventive idea.

In the drawings,

Figure 1 is a side elevation of the washer.

Figure 2 is a front elevation.

Figure 3 is a plan view of the washer.

Figure 4 is a longitudinal vertical section along the line 4—4 of Figure 1 showing a hypothetical arrangement of contents retained in position by springs and rigid supports.

Figure 5 is a horizontal section along the line 5—5 of Figure 4.

Figure 6 is a horizontal section along the line 6—6 of Figure 4.

Figure 7 is a transverse vertical section along the line 7—7 of Figure 2.

Figure 8 is an elevation of the spring and platform for cups, glasses and small articles.

Figure 9 is a plan view of the same.

Figure 10 is a vertical sectional detail of the closure means between the body and the top.

2

Figure 11 is a detail of the means of fastening the retaining springs in place.

Figures 12 and 13 show a washer in place in the sink, in upright and inverted positions respectively. In these figures the body is a cylinder adapted to revolve end over end.

Figure 14 is a section through a differently constructed washer.

Figure 15 is a side view of the washer shown in Figure 14.

Referring to Figure 1, the frame 14 consists of a baseplate 15 and standards 16 terminating in pillowblocks 17 formed with a lower half 18 and upper half 19, held together by bolts 20. The body 21 carries trunnions 22, 23 which are journaled in the pillowblocks. Trunnion 23 extends beyond the pillowblock in order to provide a shaft for a crankhandle or wheel 24 and handle 25 adapted to effect revolution of the body on the trunnions.

The cover 26 forms a waterproof closure of the top opening of the body and to assure this tightness a gasket 27 (Figures 4 and 10) is fixed to the rim of the body opening. A hole in the cover leads into a discharge spout 28 mounted on the cover. Obviously, the discharge spout may be located elsewhere in the container. The spout may be threaded and is closed by a threaded cap 29 and washer 30. The cover is held in place by hinges 31 and clamps 32 (Figures 1, 2 and 3).

The body is thus suited to be revolved end over end by the handwheel, as indicated by arrows in Figure 2. When the body is inverted and the cap removed as in Figure 13, the water runs off through a hole 33 in the frame 14 as indicated by dotted lines in Figures 1, 2, 3, 12 and 13.

Figures 4, 5 and 6 show a dish basket 34 of corrosion resisting sheet metal, wire or wood construction and very open design. The basket should slip easily into the body, but snugly enough to have no substantial movement relative to the body when the cover is clamped down and the body revolved.

Transverse members 35 divide the basket interior substantially into a number of extremely open vertical compartments for dishes. Extension coil springs 36 or other stretchable flexible means extend from one end of the basket to the other above the dishes and in contact with them, preventing displacement when the body is revolved. Springs 36 are fastened permanently at one end 37 and by a catch 38 at the other end.

An inner basket 39, of similar construction fits into basket 34 and is suitably and removably supported therein as for instance by shoulders 40

formed by deforming the sidewalls 41. This inner basket contains a multiplicity of platforms 42, 43 mounted on springs 44 in spaces 45 defined by lateral and longitudinal members 46, 47 for resiliently positioning small articles such as glasses, cups, knives, forks and spoons. The platforms 42, 43 have perforations 48 which comprise the greatest practical proportion of the total area of the platform in order to provide maximum access of water. The knives, forks and spoons are all placed together on rectangular platform 43 which has its own compartment 49.

A wire cover 50 fits over the contents of inner basket 39 and is held in place either by its own hinges and catches or by contact with the body cover 26.

In operation the dishes are slipped into their compartments as in Figures 4 and 6, and locked in place by springs 36.

Inner basket 39 is then put in place and glasses and cups, are put on their respective platforms and the knives, forks and spoons are heaped on platform 43 in compartment 49. Wire cover 50 is placed over all and preferably pressed down and locked. In the absence of a lock for cover 50 it will be held in place by closing and locking body cover 26.

A small amount of soap powder, a few inches depth of hot water, may be added before the body cover 26 is closed or through the discharge sprout 28.

A few revolutions of the body serve to wash the dishes, as the water cascades as the body revolves, and impinges on successive surfaces of the articles with the force imparted by its falling weight, and by the transverse movement of the dishes. The body is stopped in inverted position and the wash water run off, the body is returned to upright position and rinse water is run in thru the sprout, and a few more revolutions serve to rinse the dishes. The body is once again stopped in inverted position, the rinse water run off, and the contents dry themselves, since they are all in a draining position and hot enough to evaporate surface moisture.

The cascading effect of the within invention provides a forceful impingement of water on surfaces to be cleaned, a novel effect in a washer operated by hand.

It will be understood that in place of draining the waste water directly into the sink, it would be feasible and within the scope of this invention to drain the waste water into a pan or pail placed directly under the container and then carrying this receptacle to the sink for disposal.

Figures 14 and 15 show a washer of a somewhat different construction. The body 55 of the machine has the sectional area of a regular geometrical figure and the side walls 56 of the body are located at equal distances from its axis of rotation. This axis coincides with the axis of the shaft stubs 51 carrying the body 55 and mounted in bearings 58. A wheel 59 is used to rotate the body 55. Brackets 60 constituting a part of a frame 61 are used to carry the bearings 58.

A cover 62 is connected by hinges 63 to the body 55 and is locked by a suitable lock 64.

The opposite side of the body 55 carries an outlet drain 65 which forms a part of the body.

This machine is used in the same manner as the one shown in Figures 1 to 13. Dishes or other

articles 66 are placed within the body and are held in place by a wire frame 67 and springs 68 while they are being washed by the rotation of the body 55.

Thus the present invention makes it possible to provide washers of very compact design and occupying a very small space, although capable of a very large output.

Also, the within invention not only utilizes existing plumbing but can be removed after use, slid into a closet or under the sink, conserving floor space.

The extreme economy of hot water and soap, will be particularly appreciated where these things are less plentiful, and the same users will appreciate manual operation of the device.

It is apparent that the specific illustration shown above has been given by way of illustration and not by way of limitation, and that the illustrations given above are capable of wide variations and modifications without departing from the scope or intent of the present invention. For instance, all positioning means within the body may be dispensed with if the contents comfortably fill the body so as to prevent displacement on revolution, as is the case when pots and pans are washed. Other positioning means and other shapes of body may also be chosen.

What is claimed is:

30 A dish-washer, comprising a water-tight body of substantially cubic form, means revolvably supporting said cubic body at substantially the center of two parallel sides thereof to provide an axis of rotation for said body extending through said center perpendicular to said parallel sides, a rack removably located within said water-tight body for holding and positioning dishes with their surfaces parallel to said axis of rotation, said rack fitting closely into the water-tight body and revolving with it and with its water content, an elongated spring located within said body adjacent to said rack and adapted to press the dishes located in said rack against the bottom thereof, said body including a removable cover having a drain hole formed therein, a cap closing said drain hole, and a second rack removably located within said body and revolving with it and comprising means holding glasses and cups so as to drain water therefrom toward said drain hole.

CARL A. PHILIPPI.
